UNITED STATES PATENT OFFICE.

GLA R. FULLER, OF DETROIT, MICHIGAN, ASSIGNOR TO THE STUDEBAKER CORPORATION, OF SOUTH BEND, INDIANA, A CORPORATION OF NEW JERSEY.

INTERNAL-COMBUSTION ENGINE.

Application filed April 30, 1925. Serial No. 26,965.

This invention relates to internal combustion engines, and particularly to means for supporting cooling fans therefor and also lubricating the fan bearings.

5 The principal object of the present invention is to provide means for supporting such fans whereby the bearings of the same will be amply supplied with lubricant at all times.

10 Another object is to provide means in conjunction with the fan bearing for introducing lubricant into the interior of the engine of which the means forms a part, and which provides means for trapping a portion 15 of any lubricant so introduced for the sole purpose of lubricating such bearing.

Another object is to provide means for adjusting the fan bearing to tighten the fan driving belt without interfering with the 20 introduction of lubricant therethrough into the engine.

A further object is to provide a passage-way between the fan bearing and the crank-case of the engine and a breather opening 25 for the crank-case in communication with the fan bearing, whereby the lubricant carrying vapors breathed out from the crank-case during the operation of the engine will deposit a portion of such lubricant upon the 30 fan bearing, and will deposit another portion of such lubricant in a pocket below said bearing where it may be carried up to the bearing by suitable means.

The above being among the objects of the 35 present invention the same consists of certain features of construction and combinations of parts to be hereinafter described with reference to the accompanying drawings, and then claimed, having the above 40 and other objects in view.

In the accompanying drawings which illustrate a suitable embodiment of the present invention and in which like numerals refer to like parts throughout the several different 45 views,

Figure 1 is a partially broken side view of the front end of an internal combustion engine embodying the present invention.

Figure 2 is an enlarged view of the fan support and co-operating parts looking in the same direction as Figure 1.

Figure 3 is a sectional view taken on the line 3—3 of Figure 2.

Figure 4 is a sectional view taken on the line 4—4 of Figure 2.

Figure 5 is a sectional view taken longitudinally through the center of the fan bearing as on the line 5—5 of Figure 3.

Figure 6 is a fragmentary sectional view taken on the line 6—6 of Figure 3.

Figure 7 is a view taken from the pivoted side of the cap covering the combined oil and breather opening, showing the manner of pivoting the cap to the bearing housing, a portion only of the housing being shown.

Figure 8 is a sectional view taken on the line 8—8 of Figure 7.

In the drawings is shown an internal combustion engine having a cylinder block 10, an oil pan 11, which forms with the lower part 70 of the cylinder block 10 what is commonly known as the crank-case, and a chain or gear housing 12 bolted to the forward face of both the cylinder block 10 and oil pan 11, the housing 12 enclosing suitable mechanism 75 for driving an accessory drive shaft 13, cam shaft (not shown) or other necessary parts. The upper face of the housing 12 is formed to provide a flat horizontal attaching surface, the center of which is cut out to form 80 an opening 14 (Figure 4) therethrough for a purpose to be hereinafter explained. Attached to this upper face of the housing 12 by cap screws 15 is an angularly upwardly extending hollow supporting member 16 terminating at its upper and forward end in an annular seat 16' to which is pivotally secured by a bolt 17 and nut 18 (Figure 6) a hollow fan supporting member 19 having a complementary annular seat 17', the hollow interior 90 of the member 19 being in communication with the hollow interior of the member 16 through the center of the complementary annular seats just described. The upper or free end of the member 19 is enlarged to 95 form a cylindrical housing and is provided on its upper surface with an upstanding integral collar 20 which forms an opening 21 through which lubricating oil for the engine may be introduced, the oil in such cases 100 flowing down through the member 19 into the member 16 and thence through the opening 14 into the housing 12 from which it drains into the oil pan 11 in the usual manner.

105 A cap 22 is pivoted by a pin 23 to an ear 24 on the side of the collar 20 to cover the opening 21, it projecting out over and out of contact with the collar 20, and being held out of contact with the same by means of a 110

2

second ear 25 against which it normally rests, to provide an opening therearound connecting the interior of the engine with the atmosphere to allow for the "breathing" of the crank-case. The cap 22 is provided with two downwardly turned spaced ears 26 (Figure 7) to which the pin 23 is pivoted. These ears are each provided with a key-hole slot 27, the enlarged portion of which is slightly larger than the diameter of the pin 23. The pin 23 is provided with a peripheral groove 28 (Figure 7) adjacent each end thereof the bottom diameter of which is slightly smaller than the width of the small portion of the slot 27 and which grooves are spaced apart to correspond with the spacing of the ears 26 on the cap 20. In assembling, a spring 29 of the shape shown is sprung over the laterally projecting bossed portions 20 of the ear 24, the cap 20 is placed in position but with the enlarged portion of the slot 27 in line with the opening in the ear 24 provided to receive the pin 23, and the pin 23 is inserted in place, the pressure of the spring 29 forcing the pivoted end of the cap 20 upwardly so as to cause the narrow portion of the slot 27 to engage the grooves 28 in the pin 23, thereby holding the latter against axial movement, and forcing the free end of the cap 20 down against the ear 25. The forward face of the cylindrical free end housing portion of the member 19 is provided with an axially positioned elongated bearing portion 30 (Figure 5) lined with a bushing 31 and the open rear face is closed by an axially coincident forwardly extending flanged bearing member 32 also lined with a bushing 31. Rotatably supported in the bushings 31 is the shaft 33 for the cooling fan 34, on the rearwardly projecting end of which is threaded a drive pulley 35. The pulley 35 is driven by means of a belt 37 from a similar pulley 36 secured to the accessory shaft 13. Means comprising a screw 38, threaded vertically into the base of the member 16, the head of which bears against the under face of the free end of the member 19, is provided to raise or lower the free end of the member 19 about the bolt 17 as a center to tighten or loosen the belt 37 as may be required. A collar 39 secured to the fan shaft 33 between the bushings 31 prevents axial movement of the shaft 33. A dam 40 (Figure 3) provided between the cylindrical free end portion of the member 19 and the body portion thereof acts to form an oil retaining pocket 41 below the shaft 33. Suitable wicks 42 carried by drilled screws 43 threaded through the member 19 at the bottom of the pocket 41, and backed by coil springs 44 extend from the bottom of the pocket 41 up through the bearings 30 and 32 and bushings 31 to the shaft 33 which they bear against, carrying oil from the pocket 41 up to the shaft 33 for the pur-

pose of lubricating the same, or if desired, other means, such as ring oilers, may be suitably used for the same purpose. Suitable drain passages 45 are provided adjacent the outer ends of both bushings 31 to prevent oil from being carried out of the member 19 along the shaft 33, and an oil throw-off ring 46 is provided at the extreme forward end of the collar 30 to prevent any oil that may work past the forward drain 45 from working out on to the fan 34.

From the above description it will be seen that the opening 21 affords a means for introducing lubricating oil into the oil pan 11 of the engine, and when such oil is introduced into the opening 21, not only will it be poured directly on the fan shaft bearings, but a certain amount will be trapped in the pocket 41 where it forms a supply which may be slowly elevated by the wicks 42 to 85 the fan bearings. In addition, the opening 21 also forms a breather opening for the crank-case of the engine as previously described, and when the oil laden vapor is breathed out of the opening 21 during the 90 operation of the engine, oil will be deposited therefrom on the fan shaft bearings, affording additional means for lubricating the same, and, further, particles of oil from such vapor will be collected on the interior walls 95 of the free end of the member 19 and will drain down into the pocket 41 to be picked up by the wicks 42, thus providing a means for constantly replenishing the supply of oil in the pocket 41. In view of the fact 100 that the lubrication of such bearings has been a constant source of trouble in such engines, it will be readily apparent that the means provided will be of great value in overcoming the difficulty heretofore experienced, and that when this, together with the simple belt adjusting means is considered, a 105 very satisfactory construction results, which overcomes the objections heretofore encountered.

Formal changes may be made in specific embodiment of the invention described without departing from the spirit and substance of the broad invention, the scope of which is commensurate with the appended claims. 115

What I claim is:—

1. In combination with an internal combustion engine, a hollow fan support pivotally mounted thereon, the interior thereof being in communication with the crank-case 120 of said engine, a fan shaft rotatably supported at the free end of said support, and an opening in said support above said fan shaft for admitting lubricant to said shaft and crank-case.
2. In combination with an internal combustion engine having a crank case, a hollow support pivotally mounted on said engine and in open communication with said crank case, a cooling fan and a shaft therefor, said 130

- shaft rotatably mounted in bearings in the free end of said support, and means above said bearing connecting the interior of said support with the atmosphere.
- 5 3. In combination with an internal combustion engine having a crank-case, a cooling fan, and a shaft for said fan, a hollow support for said shaft pivotally mounted on said engine, the interior thereof being in communication with said crank-case and the free end thereof provided with bearings for said shaft, means for adjusting the vertical position of the free end of said support, and a crank-case breather opening in said support at a more remote point from said crank-case than said bearings.
- 10 4. In combination with an internal combustion engine having a crank-case, a cooling fan, and a shaft for said fan, an adjustable hollow supporting member on said engine, the interior thereof being in communication with said crank-case, bearings in said support for said shaft, a crank-case breather opening in said support at a point more remote from said crank-case than said bearings, a lubricant pocket in said support below said bearings, and means for elevating lubricant from said pocket to said bearings.
- 15 5. In combination with an internal combustion engine having a crank-case, a cooling fan, and a shaft for said fan, a hollow supporting member pivotally secured at one end to said engine with its interior in communication with said crank-case and provided with bearings for said shaft at its free
- end, a crank-case breather and oil-filler opening connecting the interior of said member with said atmosphere at a point more remote from said crank-case than said bearings, a dam in said member between said bearings and the point of pivot of said member forming a pocket for collecting lubricant introduced into said opening or deposited on the walls of said member, and means for carrying lubricant from said pocket to said bearings.
- 20 6. In combination with an internal combustion engine, a hollow adjustable fan support provided with fan shaft bearings and having its interior in communication with the crank-case of said engine, an oil breather opening in said support, means for trapping oil deposited during the breathing of said crank-case on the interior walls of said support, and means for leading the oil so trapped to said bearings.
- 25 7. In combination with an internal combustion engine, a hollow, adjustable fan support provided with fan shaft bearings and having its interior in communication with the crank-case of said engine, an oil filler opening in said support above said bearings, a pocket below said bearings for trapping a portion of any oil introduced into said opening, and means for leading the oil so trapped to said bearings.

Signed by me at Detroit, Michigan, U. S. A., this 27th day of April 1925.
